UNITED STATES PATENT OFFICE.

ALBERT C. GAST, OF ST. JOSEPH, MICHIGAN.

CIGAR-CUTTER.

No. 873,365.

Specification of Letters Patent.

Patented Dec. 10, 1907.

Application filed May 26, 1906. Serial No. 318,821.

To all whom it may concern:

Be it known that I, ALBERT C. GAST, a citizen of the United States of America, and resident of St. Joseph, Berrien county, Michigan, have invented a certain new and useful Improvement in Cigar-Cutters, of which the following is a specification.

My invention contemplates a novel form of cigar cutter adapted for use also as an advertising device.

In the accompanying drawings, Figure 1 is a perspective of a cigar cutter embodying the principles of my invention. Fig. 2 is a plan of the same. Fig. 3 is a section on line 3—3 of Fig. 2. Fig. 4 is a section on line 4—4 in Fig. 2. Fig. 5 is a detail view of the knife. Fig. 6 is an end view of the cigar cutter.

As thus illustrated, the body A of the cigar cutter is composed of a single blank suitably shaped and folded upon itself to provide superimposed side walls a and a . These side walls are connected by two eyelets B and C. The two side walls are provided with registering openings a^1 and a^2 . At its upper end, 25 the said body has a notch a^3 formed by a central opening in the said blank. The sheet metal knife D is provided with a finger opening d , a slot d^1 adapted to engage the eyelet C, and a V-shaped knife-edge d^2 adapted to coöperate with the openings a^1 and a^2 in cutting off the tip of the cigar. The folded end portions a^4 and a^4 of the blank engage the side edges of the knife and hold the same against lateral displacement. The 35 knife is also guided, of course, by the eyelet C. In this way, the knife slides back and forth between the two side walls of the body A, the side walls and knife forming three superimposed layers. Any suitable material, 40 such as celluloid, paper or sheet metal, can be employed for the said blank from which the body is made. Preferably the said body is rectangular in shape or outline, thus affording ample space for advertising matter. At 45 the same time, the cigar cutter is of a size and shape to be conveniently carried in the pocket.

It will be seen that the side walls a — a have free edges except where integrally united at 50 their upper ends by the bent or folded portions a^4 , which latter also engage the side edges of the knife to guide the same. The rivet or eyelet C extends through the said side walls, and also through the slot d^1 in the 55 knife, to both bind or tie the side walls together and prevent edgewise displacement of

the knife. In other words, the rivet or eyelet C has a double function, as it serves as a means for preventing a spreading apart of the side walls, and as a device for preventing 60 edgewise displacement of the knife.

What I claim as my invention is:

1. In a combined cigar cutter and advertising device, the combination of a pair of flat side walls a and a , said walls having free 65 side edges, and a flat knife slidably mounted between said side walls, the said walls provided with registering openings adapted to receive the tip of a cigar, said knife provided with a slot, and means extending through the 70 slot to guide the knife and retain the side walls together, the side walls and interposed knife arranged in three superimposed layers, as set forth.

2. In a combined cigar cutter and advertising device, the combination of a folded blank A forming the body of the cigar cutter, affording space for advertising matter, and a knife slidably mounted between and guided by the folded end portions a^4 and a^4 of said 80 blank, said body having an opening adapted to receive the tip of a cigar, said blank having flat side portions which, with the interposed knife, form three superimposed layers, each layer having a free side edge and a free 85 end edge.

3. In a combined cigar cutter and advertising device, the combination of a body A composed of a folded blank having integrally connected side walls a , said walls each having at least one free edge, openings a^1 and a^2 adapted to receive the tip of a cigar, eyelets B and C connecting and retaining the two side walls together, a knife D slidably mounted between the flat opposing surfaces of said 95 side walls, the outer end of said knife provided with a finger opening d , a slot d^1 engaged by the eyelet C, and a cutting edge d^2 at the inner end of the knife, substantially as set forth.

4. In a cigar cutter, a pair of flat walls each having one or more free edges, a flat knife intermediate said walls, there being a slot in said knife, a handle on one end of said knife for reciprocating the same endwise, and 105 means extending through the said slot to guide and limit the endwise movements of the knife, and to bind the said walls together, said walls spaced apart by the thickness of said knife, the body of said cigar cutter providing oppositely facing smooth flat surfaces 110 affording ample space for printed matter, the

- handle of the knife being provided with an opening adapted to receive a finger while said body is grasped by the thumb and other fingers of the same hand, as set forth.
5. In a cigar cutter, a pair of side walls each having one or more free edges, a flat knife interposed flatwise between said walls, there being a slot in said knife, means integral with end of said walls for engaging the side edges of the knife, a handle on one end of said knife for reciprocating the same endwise, and means extending through said slot to bind and hold the said walls together and limit the endwise movements of the knife, said walls spaced apart by the thickness of said knife, the body of said cigar cutter providing oppositely facing smooth flat surfaces affording ample space for printed matter, the handle of the knife being provided with an opening adapted to receive a finger while said body is grasped by the thumb and other fingers of the same hand, as set forth.
6. In a cigar cutter, a blank folded to provide side walls each having at least one free edge, a flat knife interposed flatwise between and covered by said walls, said walls provided with openings to receive the tip of the cigar, means for binding said walls together, a handle on one end of said knife for reciprocating the same endwise, and means engaging the parallel side edges of the knife to guide and prevent lateral displacement of the same, the body of said cigar cutter providing oppositely facing smooth flat surfaces affording ample space for printed matter, the handle of the knife being provided with an opening adapted to receive a finger while said body is grasped by the thumb and other fingers of the same hand, as set forth.
40. 7. A cigar cutter comprising a reciprocating knife provided with a longitudinal slot, a body composed of a blank folded about said knife and provided with integral portions engaging the side edges of the knife at the folded end of the said body, and means extending through said body and slot to guide the knife and keep the blank folded and limit the endwise movements of the knife, the body of said cigar cutter providing oppositely facing smooth flat surfaces affording ample space for printed matter, the handle of the knife being provided with an opening adapted to receive a finger while said body is grasped by the thumb and other fingers of the same hand, as set forth.
8. A cigar cutter comprising a rectangular body composed of two side walls integrally and flexibly connected at their upper ends, a flat knife extending between said walls and provided with a slot, and means extending through the body and slot to keep the said walls against the knife, and to prevent lateral displacement of the knife, said integral and flexible connection at the upper ends of the said walls engaging the side edges of the knife to guide the same, and said walls having free edges except where integrally connected at the ends thereof.
9. A cigar cutter comprising a flat knife, a body composed of a blank of sheet material folded transversely of its length, and upon the opposite sides of said knife, having an opening in which the knife reciprocates, and means for keeping the blank folded and guiding the knife, the body of said cigar cutter providing oppositely facing smooth flat surfaces affording ample space for printed matter, the handle of the knife being provided with an opening adapted to receive a finger while said body is grasped by the thumb and other fingers of the same hand, as set forth.
10. A cigar cutter comprising a flat knife provided with a longitudinal slot, a pair of flat rectangular side-walls disposed upon and covering the opposite sides of said knife concealing said slot, said walls each having at least one free edge extending beyond the edge of the knife, means extending through said slot to hold the side walls upon the knife and prevent edgewise displacement of the latter, and to limit the endwise movements of the knife, said knife provided with a single projecting handle or end portion extending beyond the said walls at one end thereof, the body of said cigar cutter providing oppositely facing smooth flat surfaces affording ample space for printed matter, the handle of the knife being provided with an opening adapted to receive a finger while said body is grasped by the thumb and other fingers of the same hand, as set forth.
11. A cigar cutter comprising a flat metal knife having a cutting edge at the inner end thereof, a body composed of an integral non-metallic blank of thin sheet material folded upon and embracing said knife, said blank presenting two leaves or halves which embrace the knife, and metal fastening devices for keeping the blank folded, one of said fastening devices engaging the knife to guide and limit the endwise movements of the same, said knife having a projecting handle by which it is reciprocated endwise, the body of said cigar cutter providing oppositely facing smooth flat surfaces affording ample space for printed matter, the handle of the knife being provided with an opening adapted to receive a finger while said body is grasped by the thumb and other fingers of the same hand, as set forth.

Signed by me at St. Joseph, Mich., this 15th day of May 1906.

ALBERT C. GAST.
